FUSE LINK

Eugene F. Boothe, St. Louis, Mo., assignor to
 James R. Kearney Corporation, St. Louis, Mo.,
 a corporation of Missouri

Application June 22, 1945, Serial No. 601,000

9 Claims. (Cl. 200—135)

1

This invention relates generally to fuse links of the type adapted for employment in association with electrical protective devices, such as fuse switches and cutouts, and more specifically to such fuse links which are rupturable in service by passage therethrough of abnormal current, and which may be replaced in service by intact fuse links when so ruptured, the predominant object of the invention being to provide such a fuse link which is of such improved construction and arrangement that it possesses certain desirable rupturing characteristics, and, also, is of the required tensile strength to enable the fuse link to perform its intended function in a highly efficient manner.

Some years prior to this invention a fuse link structure was devised which included an element wire and a strain wire that were attached to suitable terminals. This fuse link construction gave a fairly steep time-current curve which was found to be objectionable in some instances, in that a fuse link which would operate as desired on a high value of fault current would not provide sufficient protection at low values of fault current.

Subsequently, in an endeavor to provide a fuse link construction which would give a more gradual slope in the long time range, a fuse link construction was developed which consisted of two element members that were lapped and soldered at their point of lapping relation. On high values of fault current, in the use of this type of fuse link, melting would take place at a single thickness element section, and apart from the lapped section of the element members, thus giving substantially the same steep time-current curve obtained in the use of the earlier fuse link construction referred to immediately above. On lower values of fault current, the soldered joint of the lapped type of fuse link construction would melt, thereby giving a time-current curve which was somewhat better for certain applications, but the tensile strength of this construction was found to be insufficient for service requirements, inasmuch as the soldered joint would, in many cases, gradually pull apart, when subjected to normal service tension, and the fuse link would open even though the current passing therethrough had not been above normal value.

The fuse link structure of the present invention is of such improved and unique construction and arrangement that the objections recited above as being present in connection with the use of earlier fuse link structures, are eliminated, said improved fuse link structure of the present

2

invention providing the desired slow sloping time-current curve, and at the same time being possessed of the necessary high tensile strength to permit the improved fuse link structure to perform its intended function in a highly efficient manner.

Fig. 1 is a view partly in elevation and partly in longitudinal section illustrating the improved fuse link structure.

10 Fig. 2 is a cross-section taken on line 2—2 of Fig. 1.

Fig. 3 is a cross-section taken on line 3—3 of Fig. 1.

Fig. 4 is a view, partly in vertical section and partly in elevation, which illustrates a modified form of the invention.

In the drawing, wherein is shown for the purpose of illustration, merely, one embodiment of the invention, A designates in Fig. 1 the improved fuse link generally. The fuse link A is provided at one of its ends, the upper end as the fuse link is illustrated in Fig. 1, with a terminal member 1. The terminal member 1 is provided with a substantially circular portion 2

25 having a circumferential face which is milled, or otherwise roughened, there being a neck portion 3, of slightly reduced diameter, extending upwardly from said portion 2 which integrally joins said portion 2 and a flange portion 4 of increased diameter. The flange portion 4 has extended upwardly therefrom a screwthreaded shank portion 5 on which is mounted a terminal button 6, said terminal button being provided with a screwthreaded opening in which the

35 screwthreaded shank 5 of the terminal member 1 is screwthreadedly received so that the lower face of the terminal button abuts against the upper face of the flange portion 4 of said terminal member 1. The terminal member 1 includes, also, a hollow, lower portion 7 which is integrally joined to the circular portion 2 of said terminal member by a neck portion 8.

Secured to the terminal member 1 is strain wire 9 which is formed of material that is of high tensile strength and low electrical conductivity, the upper end portion of said strain wire 9 being inserted into the hollow portion 7 of the terminal member 1 and said hollow portion 7 being subjected to a swaging operation so as to

50 cause said strain wire to be securely gripped by said hollow portion 7 of the terminal member 1. The opposite end portion of the strain wire 9 is introduced into a lower terminal member 10 which forms a part of the fuse link structure, this lower terminal member 10 being hollow so

as to receive said end portion of the strain wire and the strain wire being securely fixed to the lower terminal member by subjecting said lower terminal member to a swaging operation.

The improved fuse link A includes a pair of electrical conductive elements 11 and 12 which are formed of material characterized by being of high electrical conductivity and relatively low tensile strength. The element 11 has an end portion thereof extended into the hollow portion 7 of the terminal member 1, and this end portion of said element 11 is securely gripped by said hollow portion because of the swaging operation to which said hollow portion is subjected. Likewise, the conductive element 12 has an end thereof extended into the hollow, lower terminal member 10, and this extended end portion of said conductive element 12 is secured to said lower terminal member 10 by the swaging operation to which it is subjected.

As is shown in Fig. 1, the inner, adjacent ends of the conductive elements 11 and 12 are spaced apart a considerable distance, and said conductive elements 11 and 12 are electrically joined by a spirally extended conductive element 13 which is formed of material characterized in accordance with the material from which the conductive elements 11 and 12 are formed. The intermediate portion of the spirally extended conductive element 13 embraces the strain wire 9 and the opposite end portions of said spirally extended conductive element respectively embrace the strain wire 9 and end portions of the conductive elements 11 and 12. Preferably, the opposite end portions of the spirally extended conductive element 13 are more closely coiled than is the intermediate portion of said spirally extended conductive element, the closely coiled portion at one end of the spirally extended conductive element 13 being secured by suitable solder to the conductive element 11, while the closely coiled portion at the opposite end of said spirally extended conductive element 13 is secured by suitable solder to the conductive element 12. It will be noted by reference to Fig. 1 that the lower terminal member 10 has secured thereto a flexible conductor 14, an end portion of said flexible conductor being extended into said lower terminal member and being gripped thereby by a swaging operation to which said lower terminal member is subjected.

Arranged in embracing relation with respect to portions of the strain wire 9 and the conductive element 11 is a short tube 15 which is formed of fiber, or other suitable electrical insulating material, said tube abutting at one of its ends against the closely coiled end portion of the spirally extended conductive element 13 which is soldered to said conductive element 11. Interposed between the opposite end of the tube 15 and the lower face of the portion 7 of the terminal member 1, is a coil spring 16, said coil spring being under compression between said tube 15 and said portion 7 of the terminal member 1 so that it tends to move said tube downwardly. The improved fuse link structure includes, also, an outer tubular member 17, formed of suitable insulating material, which embraces the conductive elements 11 and 12 and the strain wire 9, together with adjacently located parts of the fuse link structure, the upper end of said tubular member abutting against the lower face of the flange portion 4 of the terminal member 1, and said tubular member being frictionally gripped by the milled circumferential face of the portion 2 of

50 said terminal member 1 so that it is held in place.

When tension is applied to the improved fuse link disclosed herein, when same is in service, the line of tension is through the button 6, the terminal member 1, the strain wire 9, the lower terminal member 10, and the conductor 14. Thus the conductive elements 11, 12, and 13, and the soldered joints which connect said conductive elements are relieved of all tension to which the fuse link is subjected because of its use in service. The normal electrical path through the fuse link is through the button 6, the terminal member 1, the conductive elements 11, 13, and 12, the lower terminal member 10, and the conductor 14. The strain wire 9 is in parallel with the conductive elements 11, 13, and 12, but the conductivity ratio is such that but little current flows through said strain wire as long as the conductive elements 11, 12, and 13 are intact and are electrically connected.

The flow of current through the conductive elements 11, 12, and 13 tends to heat the soldered joints which connect said conductive elements together, and when the current reaches a predetermined value, said soldered joints melt. When this occurs the force of the coil spring 16 moves the tube 15 downwardly so as to strip the upper end portion of the spirally arranged conductive element 13 from the lower end portion of the conductive element 11, the force of said coil spring moving the spirally arranged conductive element 13 bodily, longitudinally of the strain wire 9 so as to provide a substantial gap between the upper end of the spirally arranged conductive element 13 and the conductive element 11, and the lower portion of said spirally arranged conductive element 13 moving downwardly with respect to the conductive element 12. Thus the normal conductive electrical path through the fuse link is broken, and all of the current then flows through the strain wire which melts immediately, and passage of current through the fuse link is completely interrupted. When, in the use of the improved fuse link, the fault current exceeds a higher predetermined value, one of the conductive elements 11, 12, or 13, will melt before the soldered joints have time to melt and separate and when this happens the current path is transferred to the strain wire which immediately melts to interrupt passage of current through the fuse link.

The force which the coil spring 16 exerts, through the tube 15, against the soldered joint which joins the conductive elements 11 and 13 is sufficient to separate said conductive elements 11 and 13 only after the soldered joints which join the conductive elements 11, 12, and 13, have melted; that is to say, said force of the coil spring is low relative to the strength of the soldered joints at normal load temperatures. The soldered joints which join the conductive elements 11, 12, and 13 are thus subjected only to a safe, low constant force, and mechanical failure which might otherwise result from external tension applied to the fuse link in use, is eliminated. An important consideration in this connection is that external tensions to which fuse links are subjected in service vary between rather wide limits, and this variation caused fuse links of the types heretofore employed to vary between correspondingly wide time-current limits. In the case of the fuse link of the present invention, however, the improved method of relieving the soldered joints from external tension gives greater time-current curve accuracy.

Still another important advantage realized in the use of the improved fuse link structure disclosed herein is that the spiral formation of the conductive element 18 increases the concentration of heat at points closely adjacent to the soldered joints. The result is that a slower or more gradually sloping time-current curve is obtained in the use of the improved fuse link. Thus, the improved construction of the fuse link disclosed herein renders it possible to obtain a more gradual time-current slope with a given type of solder at the soldered joints, while a higher temperature solder may be employed at the soldered joints to obtain a different degree of time-current curve slope.

Fig. 4 illustrates a modified form of the invention illustrated by Figs. 1, 2, and 3 of the drawing. The structure of Fig. 4 comprises an upper terminal portion 1a and a lower terminal 10a between which is extended a strain wire 9a, the upper terminal portion 1a and the lower terminal 10a being hollow and respectively receiving therein the opposite end portions of the strain wire 9a which are caused to be gripped by said upper terminal portion and said lower terminal because of swaging operations to which said upper terminal portion 1a and said lower terminal 10a are subjected.

Gripped by the swaged upper terminal portion 1a is the upper end portion of a conductive element 18, said conductive element 18, below the gripped, upper end portion thereof, being of spiral formation, and said spiral portion of said conductive element being arranged in embracing relation with respect to the strain wire 9a. Likewise, the structure of Fig. 4 includes a lower conductive element 19, which is similar to the conductive element 18, said conductive element 19 having its lower end portion gripped by the swaged, lower terminal 10a and being provided with a spiral portion that embraces the strain wire 9a. The lower portion of the spiral part of the conductive element 18 and the upper portion of the spiral part of the conductive element 19 are relatively closely coiled, and said closely coiled portions are spaced apart a substantial distance to provide a gap therebetween. Extended across the gap between the closely coiled end portions of the spiral conductive elements 18 and 19 is a substantially straight conductive element 20, the upper end portion of said conductive element 20 being secured by suitable solder to the closely coiled lower end portion of the conductive element 18, and the lower end portion of said conductive element 20 being secured by suitable solder to the closely coiled upper portion of the conductive element 19.

Arranged in embracing relation with respect to adjacent portions of the strain wire 9a and the conductive element 20 is a tube 21 which is formed of fiber, or other suitable electrical insulating material, the upper end of said tube being arranged in abutting relation with respect to lower end of the lower, closely coiled portion of the conductive element 18. The conductive element 20 has soldered, or otherwise secured thereto, an abutment element 22, and interposed between said abutment and said tube, with its opposite ends in contact with said parts, is a coiled spring 23. The coil spring 23 is under compression so that it tends to move the tube 21 and the abutment element 22 away from each other.

The flow of current through the conductive

elements 18, 19, and 20 tends to heat the soldered joints which connect said conductive elements together, and when the current reaches a predetermined value, said soldered joints melt. 5 When this occurs the force of the coil spring 23 moves the conductive element 20 downwardly, longitudinally of the strain wire 9a so as to provide a substantial gap between the upper end portion of said conductive element 20, and the lower portion of the conductive element 18. Thus, the normal conductive path through the fuse link is broken and all of the current then flows through the strain wire 9a which melts immediately, and passage of current through the 10 fuse link is completely interrupted.

I claim:

1. A fuse link comprising a pair of spaced terminal members, a strain element secured at its opposite ends to said terminal members and extended therebetween, means providing an electrical conductive path from one to the other of said terminal members, said means including an electrical conductive element, a second electrical conductive element associated with the first- 20 mentioned electrical conductive element, and meltable means for securing said second electrical conductive element to the first-mentioned electrical conductive element, and means forming part of the fuse link operable on melting of said meltable means to separate said second electrical conductive element from the first-mentioned electrical conductive element to interrupt the electrical conductive path normally provided thereby, the last-mentioned means comprising a member which embraces one of said electrical conductive elements and engages a portion of the other of said electrical conductive elements, and spring means for moving said member so as to effect separation of said second electrical conductive element from said first- 25 mentioned electrical conductive element.

2. A fuse link comprising a pair of spaced terminal members, a strain element secured at its opposite ends to said terminal members and extended therebetween, means providing an electrical conductive path from one to the other of said terminal members, said means including an electrical conductive element, a second electrical conductive element associated with the first- 30 mentioned electrical conductive element, and meltable means for securing said second electrical conductive element to the first-mentioned electrical conductive element, and means operable on melting of said meltable means to separate said second electrical conductive element from the first-mentioned electrical conductive element to interrupt the electrical conductive path normally provided thereby, the last-mentioned means comprising a tubular member 35 which embraces said first-mentioned electrical conductive element and said strain element and which engages a portion of said second electrical conductive element, and spring means for moving said tubular member so as to effect separation of said second electrical conductive element from said first-mentioned electrical conductive element.

3. A fuse link comprising a pair of spaced terminal members, a strain element secured at its opposite ends to said terminal members and extended therebetween, means providing an electrical conductive path from one to the other of said terminal members, said means including an electrical conductive element, a second electrical conductive element associated with the first- 40

mentioned electrical conductive element, and meltable means for securing said second electrical conductive element to the first-mentioned electrical conductive element, and means operable on melting of said meltable means to separate said second electrical conductive element from the first-mentioned electrical conductive element to interrupt the electrical conductive path normally provided thereby, the last-mentioned means comprising a tubular member which embraces said first-mentioned electrical conductive element and said strain element and which engages a portion of said second electrical conductive element, and spring means interposed between said tubular member and one of said pair of spaced terminal members for moving said tubular member so as to effect separation of said second electrical conductive element from said first-mentioned electrical conductive element.

4. A fuse link comprising a pair of spaced terminal members, a strain element secured at its opposite ends to said terminal members and extended therebetween, means providing an electrical conductive path from one to the other of said terminal members, said means comprising a pair of electrical conductive elements having adjacent inner ends which are spaced apart to provide a gap therebetween and which are secured respectively at their outer ends to the respective terminal members, a third electrical conductive element which extends across said gap from one to the other of said pair of electrical conductive elements, and meltable means for securing an end portion of said third electrical conductive element to one of said pair of electrical conductive elements, and means forming part of the fuse link operable on melting of said meltable means to separate said third electrical conductive element from the electrical conductive element to which it is normally secured by said meltable means to interrupt the electrical conductive path through the fuse link, the last-mentioned means comprising a member which embraces one of said electrical conductive elements and engages a portion of another of said electrical conductive elements, and spring means for moving said member so as to effect separation of said third electrical conductive element from the electrical conductive element to which it is normally secured.

5. A fuse link comprising a pair of spaced terminal members, a strain element secured at its opposite ends to said terminal members and extended therebetween, means providing an electrical conductive path from one to the other of said terminal members, said means comprising a pair of electrical conductive elements having adjacent inner ends which are spaced apart to provide a gap therebetween and which are secured respectively at their outer ends to the respective terminal members, a third electrical conductive element which extends across said gap from one to the other of said pair of electrical conductive elements, and meltable means for securing an end portion of said third electrical conductive element to one of said pair of electrical conductive elements, and means operable on melting of said meltable means to separate said third electrical conductive element from the electrical conductive element to which it is normally secured by said meltable means to interrupt the electrical conductive path through the fuse link, the last-mentioned means comprising a tubular member which embraces one of said

pair of electrical conductive elements and said strain element and which engages a portion of said third electrical conductive element, and spring means for moving said tubular member so as to effect separation of said third electrical conductive element from the conductive element to which it is normally secured.

6. A fuse link comprising a pair of spaced terminal members, a strain element secured at its opposite ends to said terminal members and extended therebetween, means providing an electrical conductive path from one to the other of said terminal members, said means comprising a pair of electrical conductive elements having adjacent inner ends which are spaced apart to provide a gap therebetween and which are secured respectively at their outer ends to the respective terminal members, a third electrical conductive element which extends across said gap from one to the other of said pair of electrical conductive elements, and meltable means for securing an end portion of said third electrical conductive element to one of said pair of electrical conductive elements, and means operable on melting of said meltable means to separate said third electrical conductive element from the electrical conductive element to which it is normally secured by said meltable means to interrupt the electrical conductive path through the fuse link, the last-mentioned means comprising a tubular member which embraces one of said pair of electrical conductive elements and said strain element and which engages a portion of said third electrical conductive element, and spring means interposed between said tubular member and one of said pair of spaced terminal members for moving said tubular member so as to effect separation of said third electrical conductive element from the conductive element to which it is normally secured.

7. A fuse link comprising a pair of spaced terminal members, a strain element secured at its opposite ends to said terminal members and extended therebetween, means providing an electrical conductive path from one to the other of said terminal members, said means comprising a pair of electrical conductive elements having adjacent inner ends which are spaced apart to provide a gap therebetween and which are secured respectively at their outer ends to the respective terminal members, a third electrical conductive element which extends across said gap from one to the other of said pair of electrical conductive elements, and meltable joints for securing the opposite end portions of said third electrical conductive element to the respective electrical conductive elements of said pair of electrical conductive elements, and means operable on melting of said meltable joints to separate an end portion of said third electrical conductive element from one of said pair of electrical conductive elements to which said end portion of said third electrical conductive element is normally secured by one of said meltable joints, the last-mentioned means comprising a tubular member which embraces one of said pair of electrical conductive elements and said strain element and which engages the separable end portion of said third electrical conductive element, and spring means for moving said tubular member so as to effect separation of said end portion of said third electrical conductive element from the electrical conductive element to which it is normally secured.

8. A fuse link comprising a pair of spaced ter-

5 minal members, a strain element secured at its opposite ends to said terminal members and ex-
tended therebetween, means providing an elec-
trical conductive path from one to the other of
said terminal members, said means comprising a
pair of electrical conductive elements having ad-
jacent inner ends which are spaced apart to pro-
vide a gap therebetween and which are secured
respectively at their outer ends to the respective
terminal members, a third electrical conductive
element which extends across said gap from one
to the other of said pair of electrical conductive
elements, and meltable joints for securing the
opposite end portions of said third electrical con-
ductive element to the respective electrical con-
ductive elements of said pair of electrical con-
ductive elements, and means operable on melt-
ing of said meltable joints to separate an end
portion of said third electrical conductive ele-
ment from one of said pair of electrical conduc-
tive elements to which said end portion of said
third electrical conductive element is normally
secured by one of said meltable joints, the last-
mentioned means comprising a tubular member
which embraces one of said pair of electrical con-
ductive elements and said strain element and
which engages the separable end portion of said
third electrical conductive element, and spring
means interposed between said tubular member
and one of said pair of terminal members for
30 moving said tubular member so as to effect sep-
aration of said end portion of said third electrical
conductive element from the electrical conductive
element to which it is normally secured.

9. A fuse link comprising a pair of spaced ter-
minal members, a strain element secured at its
opposite ends to said terminal members and ex-
tended therebetween, means providing an elec-

trical conductive path from one to the other of
said terminal members, said means comprising a
pair of electrical conductive elements having ad-
jacent inner ends which are spaced apart to pro-
vide a gap therebetween and which are secured
respectively at their outer ends to the respective
terminal members, a third electrical conductive
element which extends across said gap from one
to the other of said pair of electrical conductive
elements and which is arranged spirally about
5 said strain element and meltable joints for secur-
ing the opposite end portions of said third electrical
conducting element to the respective electrical
conducting elements of said pair of electrical
conducting elements, and means
10 operable on melting of said meltable joints to sep-
arate an end portion of said third electrical con-
ductive element from one of said pair of electrical
conducting elements to which said end portion
of said third electrical conductive element is nor-
mally secured by one of said meltable joints.
